UNITED STATES PATENT OFFICE.

WILLIAM R. PENDRY, OF CLEVELAND, OHIO.

LOADING CHUTE.

1,408,466.

Specification of Letters Patent. Patented Mar. 7, 1922.

Application filed February 24, 1921. Serial No. 447,436.

To all whom it may concern:

Be it known that I, WILLIAM R. PENDRY, a citizen of the United States, and resident of Cleveland, in the county of Cuyahoga and State of Ohio, have invented certain new and useful Improvements in Loading Chutes, of which the following is a specification.

This invention relates to apparatus used in transferring coke, coal or similar bulky materials by gravity from an overhead conveyer, bin or other place of supply into a car or similar receptacle.

One object of the invention is the provision of coke handling apparatus having an adjustable discharge chute of improved construction, whereby the materials being handled are loaded into a car or the like with a minimum amount of breakage.

Another object of the invention is to provide a discharge chute adapted to regulate and retard the flow of materials therethrough so as to lessen the velocity at which the materials are discharged from the chute.

Another object of my invention is the provision of a discharge chute having novel means whereby the flow of materials therein is controlled, and at desired intervals is stopped.

A further object of the invention is to provide a discharge chute having improved means whereby the materials discharged therefrom are leveled within a car or other receptacle and spilling of the materials over the sides of the receptacle is lessened and overcome.

A still further object of this invention is the provision of a discharge chute having improved means whereby abrasion of the chute by the materials handled thereby is avoided and largely overcome.

Further objects and advantages of my invention will be brought out in the following specification and appended claims, and are illustrated in the accompanying drawings, in which—

Figure 1 is a side elevation showing a coke screening mechanism having a discharge chute, embodying my invention, arranged for use therewith in accordance with the invention.

Figure 2 is an end elevation of the apparatus of Figure 1.

Figure 3 is a detail side elevation of the discharge chute.

Figure 4 is a cross sectional view on the line IV—IV of Figure 3.

Figure 5 is a rear elevation of the discharge chute.

Referring now particularly to Figures 1 and 2 of the drawings, the screening apparatus is shown housed in the building A, having columns 2 and roof 3. Secured in the upper part of the building is a hopper 4 mounted on supports 5 forming part of the building structure. The upper end of the hopper 4 is open and a belt conveyer (not shown) is arranged to transfer and deliver the coke, or other material being handled, into the open upper end of the hopper 4.

The lower end of the hopper is bifurcated so as to form two legs 6, 6' through which the coke is discharged into the upper end of the inclined power driven revolving screens 7 and 8. The screens which are of old and well known construction, cause the coke received at the high end thereof to slowly travel across the length of the screens and discharge it into the hopper 10. The screenings or small pieces of coke fall through the interstices in the revolving screens into the bin or hopper 9, suspended beneath the screens.

The discharge end of the hopper 10 has a tilting open end trough 11 leading therefrom, and an adjustable discharge chute B embodying my invention is pivotally mounted at one end to a shaft 12 journaled in bearings 12' secured to the supports 13. The rear end of the chute B is in telescopic engagement with the end of the chute 11 to provide a continuous passage for the material being discharged from the chute B.

The chute B is U-shaped in cross section and comprises sides 14 and a curved bottom 14', shaped substantially as an ogee curve or flattened S. The terminal or discharge end of the bottom of the chute B extends upwardly at a sharper angle than the other portion of the curve, thereby forming a recess or pocket 15 in the bottom of the chute, which is one of the essential features of this invention.

A cross bar 16 secured to the upper edges of the sides of the chute B is adapted to

be operatively connected to one end of the cable 17 of a hoist 17^a, the hoist, which may be of any suitable design, being provided for raising and lowering the lower 5 end of the chute B.

The chute B preferably is lined with tiles 18 to prevent wear by the abrasive action of the conveyed material, and binder bars 19 are arranged transversely at the opposite 10 ends of the bottom of the chute to hold the tiles 18 in position.

My improved chute is especially designed for loading coke, but it will be apparent that it may be used for handling many varieties 15 of material other than coke.

The operation of the apparatus is as follows:

The coke is discharged from a conveyer into the upper end of the hopper 4 and 20 passes downward through the legs 6 and 6' to the revolving screens 7 and 8. The screens deliver the large coke to the hopper 10, from which the coke passes through the trough 11 to the discharge chute B. Small 25 pieces of coke will accumulate in the low point 15 of the chute B. The small pieces of coke will gather in and fill up the recess or pocket 15 of the chute B, serve to engage the large coke passing therethrough, thereby 30 checking the velocity of the traveling coke and causing it to fall lightly into the car being loaded, thus lessening and preventing further breakage and permitting the coke to pile or heap up in the car, forming a good 35 top load, rather than bounding off over the sides, as is the result when using the old style gravity chutes and resulting high velocity.

When the car has been filled, the hoist 17^a 40 is set in motion and the chute section B raised, thus cutting off or preventing further discharge of coke until a new car is in position, when the chute B is again lowered to its discharge position.

One of the most important advantages of 45 my improved chute is the checking of the velocity of discharge of the coke by a cushioned retarder made up of the coke particles in the recess 15.

It will be readily apparent that various 50 modifications in the design of this device may be made in order to adapt it to various uses and for handling various materials, within the scope of the appended claims, 55 without departing from the spirit of my invention.

I claim:—

1. A chute having its bottom wall depressed adjacent its discharge end forming a shallow pocket adapted to fill with small 60 pieces of the material being conveyed and form a cushion to check the velocity of the main volume of the material passing through the chute.

2. A chute having a substantially ogee 65 curved bottom, forming a pocket adjacent its discharge end, and means for adjusting the angle of inclination of said chute.

3. A chute having a substantially S-shaped bottom forming a pocket therein at 70 the discharge terminal of said chute, and means for adjusting the angle of inclination of said chute.

4. The combination with a screening mechanism of a pivotally mounted chute 75 arranged to receive materials discharged from said screening mechanism, said chute having a substantially S-shaped bottom forming a pocket adjacent to the discharge end thereof, and said pocket being adapted 80 to gather particles of the material being handled, and form a cushion to check the velocity of the main volume of the material passing through the chute.

5. The combination with a hopper of a 85 pivoted chute, located to receive materials discharged from said hopper, said chute having a substantially S-shaped bottom forming a pocket adjacent to the discharge end thereof, said pocket being adapted to gather 90 and retain small pieces of the material being conveyed and thereby form a cushion in said chute, and means for moving said chute upon its pivot to adjust the inclined position 95 thereof.

6. The combination with a hopper of a pivoted chute, located to receive materials discharged from said hopper, said chute having a substantially S-shaped bottom forming 100 a pocket adjacent to the discharge end thereof, said pocket being adapted to gather and retain small pieces of the material being conveyed and thereby form a cushion in said chute, and means for moving said chute upon its pivot to adjust the inclined position 105 thereof, and means for raising and lowering the discharge end of said chute to vary the velocity of material flowing through said chute.

In testimony whereof, I have hereunto 110 signed my name.

WILLIAM R. PENDRY.
